INSTRUMENT FOR TREATING TEETH

Charles J. F. Jackson, Winnipeg, Manitoba,
CanadaApplication August 25, 1933, Serial No. 686,716
In Canada January 23, 1933

10 Claims. (Cl. 132—89)

The invention relates to improvements in instruments for treating teeth and an object of the invention is to provide a simple, inexpensive and efficient instrument for cleaning, massaging or medicating the teeth, particularly in any location not readily accessible, such as, in the inter-proximal areas between the teeth and also the areas adjacent to the gums.

A further object is to provide an instrument in the form of a pick or applicator carried by a handle and mounted thereon so that it can be readily removed by the user for replacement purposes and positioned such that it can be conveniently used for both cleaning, massaging or medicating purposes.

A further object is to provide a pick or applicator having a tapering end adapted to be frictionally received within a tapering hole provided in the handle and to enclose the pick in a material, such as absorbent cotton, for cleaning, massaging or medicating purposes and also serving to effectively jam the head of the pick in the hole of the handle, yet allowing of ready removal of the pick when desired for replacement purposes.

A further object is to so position the pick in relation to the handle that it can be conveniently used.

A further object is to provide a keeper carried by the handle and adapted when in use to positively prevent the loosening or escape of the pick.

With the above more important objects in view, the invention consists essentially in the arrangement and construction of parts hereinafter more particularly described, reference being had to the accompanying drawing, in which:—

Fig. 1 is a perspective view of a tooth brush having the handle thereof equipped with my instrument.

Fig. 2 is an enlarged detailed vertical sectional view longitudinally and centrally through one end of the handle.

Fig. 3 is a view similar to Figure 2 and showing the end of the handle bent at an obtuse angle.

Fig. 4 is a side view of a sharp pointed pick or applicator.

Fig. 5 is a side view of a blunt pointed pick or applicator.

Fig. 6 is an enlarged cross sectional view at 6—6 Figure 2.

In the drawing like characters of reference indicate corresponding parts in the several figures.

I have herein shown my invention as introduced on a tooth brush handle, the handle 1 having the brush 2 at one end thereof and my in-

strument at the other end thereof. The latter end of the handle is shown straight or non-bent in Figure 1 and Figure 2 and the sides thereof are rounded as shown.

In the extremity of the handle, I make a tapering hole 4 which passes entirely through the handle end, the taper being a gradual one as best shown in Figure 2. A pick or applicator 5 is supplied, which is also tapered and is adapted to be passed through the hole in the handle in the 10 manner best shown in Figure 2 and is adapted to become jammed in the hole under pressure and by virtue of the taper. The pick may be made from any suitable material and in this regard I might mention that I have found that a wooden 15 pick effectively serves my purpose.

Prior to inserting the pick in the hole, I apply a covering material 6 thereon, such as absorbent cotton and after having applied the absorbent cotton, I insert the small end of the pick in the 20 large end of the hole and then force the pick into the hole until the large end of it becomes firmly jammed in the handle hole as shown in Figure 2.

It will be observed that the covering material 25 is jammed between the wall of the hole and the large end of the pick so that the covering material as well as the pick are tightly held in place.

When a straight handle is used, the hole passes therethrough angularly so that the instrument 30 is in an angular position in respect to the handle. It can obviously be positioned, however, to obtain the same result by bending the end of the handle carrying the instrument as shown in Figure 3 and having the hole passing through the bent end 35 with its major axis positioned at right angles to the longitudinal axis of such bent handle end.

The picks used can be blunt or pointed as shown in Figures 4 and 5 and in fact may be any desired shape for operating on the teeth 40 or gums.

One can use this instrument to effectively clean, massage or medicate the inter-proximal areas between the teeth and adjacent to the gums and obviously any desired cleaning, medicinal 45 polishing, massaging or lubricating agent can be used as it will readily adhere to or be absorbed by the absorbent cotton.

With a construction as described, there is a small possibility that when one is working on 50 his teeth with the instrument, the constant back pressure on the point of the pick might loosen the pick in the hole. This possibility can be entirely removed by using a comparatively small keeper 7 slidably connected to the handle in a location 55

adjacent the hole and adapted in its forward position to overlie the head of the pick in the hole and positively prevent escape thereof. The keeper spans the end of the handle and is provided with inturned tongues or flanges 7' adapted to enter longitudinally extending receiving channels 8 formed in the sides of the handle.

The body of the handle is cut away so that the exterior face of the keeper lies flush with the face of the handle and friction is relied upon to hold the keeper in any set position. Obviously one can readily shift the keeper with his finger or thumb to a position overlying or clear of the head of the pick. A keeper of this kind is very simple and inexpensive in construction and reliable in use but of course any other means could be used for the purpose within the scope of the appended claims.

I wish it to be understood, however, that the device may be made with or without the keeper as I have found that for all practical purposes, if one effectively jams the tapered cotton covered pick in the tapered hole, it will remain fixed in place when in use. If one is careless, however, when jamming the pick, the keeper will insure of the effective holding of the pick.

What I claim as my invention is:—

1. In a dental instrument, a handle having a tapering orifice passing therethrough and a tapering instrument having the large end thereof received within said orifice and a slidable keeper recessed within the handle adjacent the large end of said orifice and endwise slidably thereover and adapted to prevent withdrawal of the instrument from said orifice.

2. A handle having a hole passing therethrough, an instrument extending from the handle and having one end contained within the hole and an absorbent material covering the instrument and jammed between the body of the instrument and the wall of the hole.

3. A handle having a tapering hole passing through one end thereof, an instrument having a tapering end adapted to enter the hole and absorbent material covering the instrument and frictionally jammed between the tapering end of the instrument and the wall of the hole.

4. A handle having a hole passing therethrough, an instrument extending from the handle and having one end received within the hole and absorbent cotton enclosing the instrument and jammed between the said end of the instrument and the wall of the hole.

5. A handle having a gradually tapering hole passing therethrough, a tapering instrument having the large end received within the hole and absorbent cotton covering the instrument and frictionally jammed between the large end of the instrument and the wall of the hole.

6. A handle having a tapering hole passing angularly through one end thereof, a tapering pick having the large end thereof received within the hole and absorbent cotton covering the instrument and frictionally jammed between the large end of the instrument and the wall of the hole.

7. A handle having a tapering hole passing through one end thereof and a tapering instrument having the large end thereof received within the hole and a keeper slidably attached to the handle and normally overlying the large end of the hole.

8. A handle having a tapering hole passing through one end thereof, an instrument having a tapering end adapted to enter the hole, an absorbent material covering the instrument and frictionally jammed between the tapering end of the instrument and the wall of the hole and normally overlying the large end of the hole.

9. A handle having a hole in one end thereof, a dental applicator extending from the handle and entering the hole and an absorbent material enshrouding the applicator and jammed between the applicator and the wall of the handle hole.

10. A handle having a tapering hole passing therethrough and a tapering instrument having the large end thereof received within the hole and a keeper attached to the handle for endwise sliding movement thereof and normally overlying the large end of the hole and adapted to prevent withdrawal of the instrument from the hole.

CHARLES J. F. JACKSON.
